INVENTOR

Wm. Alex. Wilson

UNITED STATES PATENT OFFICE.

WILLIAM ALEXANDER WILSON, OF NEEDHAM, MASSACHUSETTS.

AUTOMATIC FIRE-EXTINGUISHING SPRINKLER.

SPECIFICATION forming part of Letters Patent No. 268,970, dated December 12, 1882.

Application filed October 6, 1882. (No model.)

To all whom it may concern:

Be it known that I, WILLIAM ALEXANDER WILSON, of Needham, in the county of Norfolk and State of Massachusetts, have invented certain new and useful Improvements 5 in Automatic Fire-Extinguishing Sprinklers, of which the following is a specification.

My invention relates to that class of automatic fire-extinguishing water-sprinklers in 10 which the melting of solder by the heat of the fire allows the water under pressure to flow upon the fire so as to extinguish it.

The object of my invention is to provide a very sensitive extinguisher, so that the minimum of heat will put it in action; also to make it cheap and of simple construction. I attain 15 these objects by the mechanism illustrated in the accompanying drawings, in which—

Figure 1 is an elevation of the extinguisher 20 ready for service. Fig. 2 is an elevation the plane of which is at right angles with the plane of Fig. 1. Fig. 3 is a vertical section of the same. Fig. 4 is a detail, and Figs. 5 and 6 illustrate a modification of my invention.

25 A A' represent a block of metal, which serves as a base for attaching my device to the water-pipe. This may be attached by a screw, as shown at A, or by any other suitable device. This base-block A A' has bifurcated ears a a', as shown in Figs. 1, 2, and 5,

30 by which the straps D D are held in place. These straps are attached to the yoke C at C', and by means of the set-screw C' or any other suitable device; or by making the straps

35 D D short enough a strong pressure can be made upon the cap B, thus firmly holding it in its seat a³, as shown in Fig. 3. To insure a tight joint I use a mixture of vaseline and plumbago. By the use of this mixture I prevent 40 the joints from sticking when the cap needs removing. Before adjusting the cap I apply this mixture to the cap-seat, and then, firmly pressing down the cap by means of the set-screw C', I press the mixture into the space

45 between the cap and the adjacent metal inside the cap. The stronger the pressure of the water the more firmly it will press the mixture into the joint. I thus increase the tightness of the joint by the increase of water-pressure.

50 Attached to the upper end of the block A

A' is a deflecting-disk, a⁴, attached by means of wires at a², as shown in Fig. 3. This causes the water to splash in a spray upon the surface beneath, and leaves an open vent, which avoids any stoppage from sediment or other 55 obstructions gathering in the supply-pipes.

In constructing the straps D D, I use strips of brass, which are bent round a bit of wire, D'. This prevents the straps from slipping through the slots a' and C'. These straps are 60 bent open as seen in Fig. 4. They are then sprung together and soldered with solder melting at about 160°. By this construction I obtain an easy separation of the joints when the solder is melted. When a fire starts its heat 65 melts the solder, and, releasing the straps, the yoke C is freed from its strain. The small amount of metal in the straps D requires but little heat to melt the solder, and a high degree of sensitiveness is thus attained. The 70 water-pressure then throws off the cap B, and the water flows freely upon the fire.

In Figs. 5 and 6 is shown another form of deflector. On the inner surface of the block A A' are two spiral flanges, a⁵, which give the 75 water a circular motion in its passage from the nozzle a². The centrifugal force thereby attained causes the water to form a spray on emerging from the nozzle.

I claim—

1. In combination with the block A A', the cap B, yoke C, and set of straps D D, all operating together substantially as described.

2. In combination with the block A A', the cap B, yoke C, and set of straps D D, having 85 their ends soldered together, as and for the purposes set forth.

3. The combination of block A A', having a deflector, with cap B, yoke C, screw C', and set of straps D D, substantially as described, 90 and for the purpose set forth.

4. In automatic fire-extinguishers, the block A A', having bifurcated ears a a', the water-way of which is provided with a spiral deflector, a⁵, as and for the purpose set forth.

WM. ALEX. WILSON.
